UNITED STATES PATENT OFFICE.

CHARLES J. OLNEY, OF WALTHAM, MASSACHUSETTS, ASSIGNOR TO WALTHAM WATCH COMPANY, OF WALTHAM, MASSACHUSETTS, A CORPORATION OF MASSACHUSETTS.

HOLDER FOR BRACELET-WATCHES.

1,215,053.

Specification of Letters Patent.

Patented Feb. 6, 1917.

Application filed February 9, 1916. Serial No. 77,166.

To all whom it may concern:

Be it known that I, CHARLES J. OLNEY, a citizen of the United States, residing in Waltham, Middlesex county, State of Massachusetts, have invented certain new and useful Improvements in Holders for Bracelet-Watches, of which the following is a specification, reference being had to the accompanying drawing, forming a part hereof.

10 The object of this invention is to provide a convenient, practical and attractive device for the shipping and display of a wrist-watch and its attached bracelet.

Bracelet-watches are preferably shipped, 15 displayed and sold with the bracelet attached to the watch, but because of the difficulty in supporting the watch and the bracelet in their proper relation in such cases or holders as are commonly employed, the 20 bracelet is often detached from the watch and laid with the watch in a flat case. Not only are the watch and bracelet not displayed to the best advantage, therefore, but the retail dealer, in making a sale, must connect each watch and bracelet for exhibition 25 to the prospective customer and for trial and must then detach each bracelet from the watch before the bracelet and watch can be returned to the case or holder. The watch 30 and bracelet are thus subjected to considerable handling and much time is consumed. In accordance with this invention the case or holder is so formed as to receive the watch and bracelet when they are connected, to 35 maintain at all times the proper relation between the watch and bracelet, to keep the bracelet under proper tension so that the relation of the watch and bracelet shall not be disturbed, even during transportation, 40 and to permit the watch and bracelet to be displayed to advantage. In accordance with the invention the improved case or holder comprises a suitable box and a removable frame upon which the watch and bracelet 45 may be readily displayed and by which the bracelet is maintained under sufficient tension to preserve the proper relation between the watch and the bracelet. The invention will be more fully explained hereinafter 50 with reference to the accompanying drawing in which it is illustrated and in which,—

Figure 1 is a view showing the outer case or container in longitudinal section and the

inner frame in elevation with a watch and bracelet in position thereon.

55

Fig. 2 is a view showing the box or container in transverse section and the frame in end elevation.

60

Fig. 3 is a detail view in longitudinal section of the frame removed from the case.

Fig. 4 is a view of the same in transverse section.

65

Fig. 5 is a view of the open box or container in transverse section, the display position of the frame, watch and bracelet being indicated by dotted lines.

70

The case or container a , of any suitable dimensions and of any suitable material, is preferably provided with a cover b , which may be hinged, as at b' , the interior of the case and cover being suitably lined with plush or other desired material. Interiorly the box is provided, preferably on its long sides, with longitudinal members a' , which form ledges or shoulders a'' .

75

The frame or holder proper, to which the watch and bracelet are applied, comprises two blocks d and d' which are held apart yieldingly, as by light spiral springs d^2 , excessive separation of the blocks being prevented by retaining screws d^3 which pass freely through one of the blocks, as d' , and are threaded into the other, recesses, as at d^4 , being formed in the block d' to receive the heads of the screws. One of the blocks, as the block d , may be provided with a shallow recess d^5 to form a seat for the watch e , and the ends of both blocks are preferably grooved slightly at the lower edges, as at d^6 and d^7 , to form seats for the bracelet f . Both blocks may be covered with a covering d^8 of velvet or other suitable material, such covering being preferably made in one piece, as shown in Fig. 3, sufficient slack being provided between the two blocks to permit them to be separated by the action of the springs d^2 .

80

The block d' is narrower than the block d , so that for transportation the frame or holder may be placed within the case a , as shown in Figs. 1 and 2, the wider block d resting on the shoulders or ledges a'' while the block d' drops between them. For purposes of display the frame or holder may be drawn partly out of the case and tilted, the under side of the narrower block d' then

85

resting on the rear ledge or shoulder d^2 , as shown in Fig. 5.

In assembling the frame or holder and the watch with its bracelet the watch is placed in the seat or depression d^5 and the bracelet is slipped around the blocks, standing in the shallow grooves d^6, d^7 at the ends. The frame or holder may be collapsed by pressure to permit the watch and bracelet to be placed thereon easily and thereafter the action of the springs d^2 , limited by the screws d^3 , presses the two blocks apart and takes up the slack of the bracelet, insuring the retention of the watch and bracelet in proper relation with respect to each other and to the frame or holder.

It will be understood that various changes in details of construction and arrangement may be made to suit different conditions of use, without departing from the spirit of the invention.

I claim as my invention:

1. A holder for a bracelet-watch comprising two separable blocks to receive the watch and bracelet about them and means to press the blocks apart.

2. A holder for a bracelet-watch comprising two separable blocks to receive the watch and bracelet about them and springs to press the blocks apart.

3. A holder for a bracelet-watch comprising two separable blocks to receive the

watch and bracelet about them, means to press the blocks apart, and a flexible one-piece covering for the blocks.

35

4. A holder for a bracelet-watch comprising two separable blocks to receive the watch and bracelet about them, springs to press the blocks apart, and a flexible one-piece covering for the blocks.

40

5. A holder for a bracelet-watch comprising two separable blocks to receive the watch and bracelet about them, the blocks being recessed to form seats for the watch and the bracelet, and means to press the blocks apart.

45

6. The combination with a case having internal longitudinal shoulders, of a holder for a bracelet-watch, comprising two separable blocks to receive the watch and bracelet about them, and means to press the blocks apart.

50

7. The combination with a case having internal longitudinal shoulders, of a holder for a bracelet-watch, comprising two separable blocks to receive the watch and bracelet about them, the lower block being narrower than the upper block to enter between the shoulders of the case, and springs to press the blocks apart.

55

This specification signed this 3rd day of February A. D. 1916.
